(57) **CLAIM**

The ornamental design for candles holder, as shown and described.

DESCRIPTION

FIG. 1 is a perspective view of a candles holder showing my new design with candles in broken line for purposes of illustrating the design in condition of use;

FIG. 2 is a perspective view thereof, with the candles removed;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a top plan view thereof.

The broken lines depict environmental structure and portions of the candles holder that form no part of the claimed design.
